UNITED STATES PATENT OFFICE

95,170

DESIGN FOR A PENCIL BOX OR SIMILAR ARTICLE

George H. Baumgard, Carlstadt, N. J., assignor to Eagle Pencil Company, New York, N. Y., a corporation of Delaware

Application June 7, 1934, Serial No. 52,093

Term of patent 7 years

To all whom it may concern:

Be it known that I, George H. Baumgard, a citizen of the United States of America, residing at 544 Union Street, Carlstadt, State of New Jersey, have invented a new, original, and ornamental Design for a Pencil Box or Similar Article, of which the following is a specification, reference being had to the accompanying drawing, forming part thereof.

Fig. 1 is an end view of the box in closed position, and

Fig. 2 is a perspective view of the box in open position.

I claim:

The ornamental design for a pencil box or similar article, as shown and described.

GEORGE H. BAUMGARD.
